GRAIN DRIER

William E. Tomlinson and Ben L. Tomlinson,
Hector, Minn.

Application September 5, 1947, Serial No. 772,284

2 Claims. (Cl. 263—8)

1

This invention relates to dryers and dehydrators for drying grain and other agricultural products, and in particular and insulated housing have an endless wire mesh conveyor belt with means for feeding grain to the belt and from the housing, and means for supplying air at relatively high temperatures and also means for exhausting the air, drawing it through the grain.

The purpose of this invention is to provide an improved dryer for grain and the like wherein the grain may be subjected to intense heat and then cooled before being discharged therefrom and in which the temperature, volume and velocity of air passing therethrough, speed of the grain conveying means, and the amount of grain fed to the device, may readily be regulated.

Various devices and machines have been provided for drying and dehydrating grain and other products and although some have used steam as the heating agent, it has been found desirable to use higher temperatures for some grain. With this thought in mind this invention contemplates a grain dryer having an oil burner with circulating means for applying heat from the burner to the grain and also circulating means for cooling the grain.

The object of this invention is, therefore, to provide a unique grain dryer wherein the grain is directly subjected to the heat of a fire for efficient and rapid drying.

Another object of the invention is to provide a grain dryer having a furnace therein with heating and cooling circulating means wherein the elements may be incorporated in a unitary housing.

Another object of the invention is to provide a grain dryer having both heating and cooling means wherein independent circulating means are provided for heating and cooling.

A further object of the invention is to provide a grain dryer in which grain is subjected to intense heat and then cooled, which is of a simple and economical construction.

With these and other objects in view the invention embodies an elongated substantially rectangular shaped housing with a horizontally disposed conveyor extending therethrough, a combustion chamber below the conveyor, a cool air compartment through which the discharge end of the conveyor travels, exhaust blowers in the combustion chamber and cool air compartment, means feeding grain to the conveyor, and means discharging grain from the conveyor.

Other features and advantages of the invention consist in the details of construction, com-

bination and arrangement of parts as will be hereinafter more fully described, illustrated in the accompanying drawings, which disclose the preferred embodiment of the invention, and pointed out in the appended claims, wherein:

Figure 1 is a view showing a longitudinal section through the dryer with parts in elevation and parts broken away.

Figure 2 is a cross section through the dryer taken on line 2—2 of Figure 1.

Figure 3 is an end view of the dryer taken on line 3—3 of Figure 1, with parts broken away.

Figure 4 is a cross section through the dryer taken on line 4—4 of Figure 1, showing the screw conveyor for discharging the grain from the housing of the dryer.

Figure 5 is a detail illustrating the elevating rack and pinion for a spreader intermediate the ends of the dryer.

Figure 6 is a detail showing a section through the spreader shown in Figure 5.

Referring now to the drawings wherein like reference characters indicate corresponding parts the grain dryer of this invention includes an endless wire mesh conveyor belt 10, a feed hopper 11, a discharge screw 12, an oil burner 13, exhausters 14 and 15, and a housing 16.

The conveyor 10 is formed of wire of a mesh suitable for holding grain and this is mounted on a head pulley 17 at the discharge end, and a tail pulley 18 that is mounted on a shaft 19 in bearings 20 and the bearings are provided with take-up elements 21. The bearings with the take-up elements are mounted on supports 22 in the end of the housing. The head pulley of the conveyor is mounted on a shaft 23, having a pulley 24 thereon through which the shaft is rotated from a pulley 25 of a reduction gear by a belt 26. The reduction gear, as indicated by the numeral 27, is driven from a motor 28 by a belt 29 and pulleys 30 and 31.

The belt 10 of the conveyor travels over spaced longitudinally extending supporting bars 32 that are held by transverse struts 33 from the side walls 34 and 35 of the housing, and raker bars 36 are suspended from rigidly mounted rods 37 above the conveyor belt, as shown in Figures 1 and 2, to evenly distribute and agitate the grain as it travels through the drying chamber. The rods 37 are also mounted in the side walls 34 and 35.

The feed hopper 11 may be supplied from a garner bin or the like, and as shown in Figure 1 the hopper is formed by a partition 38 spaced from an end wall 39 of the housing, and the lower

end of the partition stops at the point 40 and is provided with a gate 41 that may be raised and lowered by a hand wheel (not shown) on a shaft 43 through pinions 44 and racks 45. The lower end of the hopper is provided with a baffle 46 to guide the grain to the belt and by adjusting the gate to the proper elevation the film of grain on the belt is readily controlled.

The screw conveyor 12 is provided on a shaft 47 which is driven from the shaft 23 of the head pulley 17 of the conveyor by a belt 48 traveling over pulleys 49 and 50, as shown in Figure 4. The screw delivers the grain from the discharge end of the conveyor to a chute 51 at the side of the housing. The screw is positioned in a semi-circular trough 52 that is positioned to receive grain from the conveyor 10.

Below the discharge end of the conveyor is an oil burner 13, supplied from an oil pump 53 and provided with air under pressure by a blower 54 actuated by a motor 55, which also drives the oil pump through a belt 56 and pulleys 57 and 58. The oil burner is positioned in a combustion chamber 59 lined with suitable firebrick 60 and a horizontally disposed insulating partition 61 is provided above the combustion chamber to insulate a substantial portion of the discharge end of the conveyor from the heat to provide a cooling chamber that is separated from the drying chamber by a vertically disposed transverse partition 62. The partition 62 is provided with an opening 63 through which the upper belt of the conveyor passes and a gate 64 is provided on the partition to regulate the open area above the belt. The lower end of the gate 64 is provided with an apron 65 and the elevation of the gate may be adjusted by a handwheel 66 on a shaft 67 through pinions 68 and racks 69.

The cooling chamber is separated from the end 70 of the housing by a partition 71 providing a compartment 72 for the motors and other equipment. Check doors 73 and 74 are provided in the side walls with a door 73 positioned in the dryer and a door 74 in the cooling chamber. Openings 75 and 76 are also provided in the side walls 34 and 35 to admit cooling air to the cooling chamber below the upper belt of the conveyor and these openings are positioned above the insulated partition 61, as shown in Figure 1.

An exhauster 14 with a motor 78 is provided in the upper wall 79 of the housing and the exhauster is located adjacent the intake hopper so that a forced draft is provided to draw air through the combustion chamber and through grain on the belt of the conveyor; and a similar exhauster 15 with a motor 81 is also mounted in the upper wall 79 and located in the cooling chamber to maintain a circulation of air therethrough for cooling.

The complete housing 16 is formed with insulated walls having inner and outer panels with insulating material between the panels and suitable inspection and cleanout doors 82 and 83 respectively may be located at convenient points therein.

The size of the housing and also the relative sizes of compartments therein may be changed as desired. The proportionate sizes of the heating and cooling chambers in the housing may also be changed by adjusting the partition 62 the upper part of which is suspended from a plate 84 on the under side of the upper wall 79 and the plate is held by bolts 85 and 86 that extend through slots 87 and 88 in the wall 79. The side wall 35 is also provided with a slot 89 which is closed by a

cover plate 90 against the inner surface of the wall, and the gear shaft 67 of the partition 62 extends through the slot 89 with the hand wheel 66 on the outer end.

The construction of the dryer will be readily understood from the foregoing description. In use grain is supplied to the feed hopper 11 from which it is fed to the upper belt of the conveyor and as it is carried through the housing the exhauster 14 draws the hot air from the combustion chamber through the grain thereby accelerating drying, and then as the grain passes the partition 62 the exhauster 15 draws cool air through it so that it is cooled before it is discharged from the housing by the screw conveyor 12.

It will be understood that modifications may be made in the design and arrangement of the parts without departing from the spirit of the invention.

What is claimed is:

1. A continuous grain dryer having in combination an elongated housing having a receiving end and a delivery end, an endless, porous conveyor extending horizontally throughout substantially the length of said housing and medially disposed relative to the height thereof, a hopper in the receiving end of said housing adapted to deliver continuously a stratum of grain upon the receiving end of said conveyor, means including a spout for delivering dry grain from the delivery end of said housing, a blast type burner mounted in the lower portion of said housing below said conveyor and directed longitudinally and centrally of said housing toward the receiving end thereof, a transverse partition dividing the interior of said housing into a larger hot chamber extending from a point inwardly of said burner to the receiving end of said housing and a cooling chamber extending from said partition to the delivery end of said housing, partitioning means enclosing said burner and its combustion chamber and including walls spaced from the side walls of said housing adjacent the delivery end and forming with said side walls, upwardly extending ducts forming a part of said cooling chamber and communicating with the upper unobstructed portion of said chamber through said porous conveyor and the grain carried thereon, said transverse partition having an aperture in the central portion thereof for accommodating said conveyor and the stratum of grain carried thereby, the sides of said housing having cool air intake passages adjacent the bottom thereof in communication with said ducts and a large blower mounted centrally in the upper portion of said heating chamber above said conveyor and having air inlets at both ends thereof and a tangential discharge extending through the top of said housing whereby hot air and products of combustion will be drawn and circulated upwardly through said porous conveyor and the stratum of grain thereon and then discharged from the dryer and whereby cool air will be drawn through said inlets and upwardly through said ducts and through the delivery portion of said conveyor and circulated in said cooling chamber.
2. A continuous grain dryer having in combination an elongated housing having a receiving end and a delivery end, an endless porous conveyor extending horizontally throughout substantially the length of said housing and medially disposed relative to the height thereof, a hopper in the receiving end of said housing adapted to deliver a stratum of grain over the full width of

the receiving end of said conveyor, means including a spout for delivering dry grain from the delivery end of said housing, heating means mounted in the lower portion of said housing for delivering hot air below said conveyor and to the intermediate portion of said housing and the portion adjacent the receiving end, a transverse partition dividing the interior of said housing into a larger heating chamber and a cooling chamber which extends from said partition to the delivery end of said housing, said housing having cool air inlets adjacent the lower portion thereof and communicating with said cooling chamber, said cooling chamber being in communication with said heating chamber, suction blower means mounted within said housing above said conveyor for drawing air and gaseous material upwardly through said conveyor and the stratum of grain thereon and for discharging the drawn air and gaseous matter exteriorly of said housing and a series of spaced rake bars travers-

ing the upper leaf of said conveyor and disposed substantially vertically in parallel lines beginning inwardly of the receiving end of said housing, said rake bars each having a series of depending tines extending to points slightly above the upper leaf of said conveyor for breaking up and mildly agitating and distributing the grain as it is passed therethrough by the travel of said conveyor.
